UNITED STATES PATENT OFFICE.

JAMES C. DAVIDSON AND CALVIN C. DAVIDSON, OF DENVER, COLORADO.

DESIGN FOR A BOTTLE.

SPECIFICATION forming part of Design No. 12,965, dated June 13, 1882.

Application filed April 12, 1882. Term of patent 14 years.

To all whom it may concern:

Be it known that we, JAMES C. DAVIDSON and CALVIN C. DAVIDSON, citizens of the United States, residing at Denver, in the county of Arapahoe and State of Colorado, have originated and invented a new and useful Design for Bottles; and we do hereby declare that the following is a full, clear, and exact description thereof, reference being had to the accompanying drawings, forming a part of this specification.

Figure 1 is a front view, Fig. 2 a rear view, Fig. 3 a side view, of our newly-designed bottle.

According to our design the exterior shape or configuration of the bottle, viewed from either front or back, is perfectly square, except that the side lines or edges, *a*, at their upper ends, extend inward and upward to the horizontally-straight top line, *b*, which they join. The sides *c* extend up from the bottom to the point *d* in a vertically-straight line. From the point *d* the sides extend inwardly and upwardly, and form shoulders *e*, of flat shape. An outwardly-extending ridge or bead, *f*, extends around each face of the bottle, and also around each side thereof, from the bottom to the shoulders *e*.

Within the bead *f*, surrounding each face, is a circle, *g*, surrounded by a bead or ridge, *h*, of a height corresponding to the height of the ridge or bead *f*. Upon each side is formed a monogram consisting of the letters "W. C. C. Co.," as shown.

i represents the neck of the bottle, and *k* represents the stopper.

The bottle may be manufactured of glass, earthenware, or any other suitable or desired material, and can be readily molded or formed by the ordinary devices for producing bottles or other articles by pressure.

What we claim is—

A bottle having square corners, a ridge or bead surrounding each face and each side thereof, and a bead-surrounded circle in each face, substantially as shown and described.

In testimony that we claim the foregoing as our own we affix our signatures in presence of two witnesses.

JAMES C. DAVIDSON.
CALVIN C. DAVIDSON.
